UNITED STATES PATENT OFFICE

172,805

FORK

Jean O. Reinecke, Oak Park, Ill., assignor to
George W. Emmert, Winnetka, Ill.

Application February 17, 1954, Serial No. 29,084

Term of patent 3½ years

(Cl. D44—29)

To all whom it may concern:

Be it known that I, Jean O. Reinecke, a citizen of the United States, residing at Oak Park, in the county of Cook and State of Illinois, have invented a new, original, and ornamental Design for a Fork, of which the following is a specification, reference being had to the accompanying drawing, forming a part hereof, in which:

Fig. 1 is a plan view of the top or front side of a fork embodying my new design;

Fig. 2 is a similar view of the back side of the fork;

Fig. 3 is a side view thereof;

Fig. 4 is a longitudinal cross-section taken substantially along the longitudinal center line of the fork;

Fig. 5 is a transverse cross-section taken along the line 5—5 in Fig. 1; and

Fig. 6 is a similar cross-section taken along the line 6—6 in Fig. 2.

I claim:

The ornamental design for a fork, substantially as shown.
